(57) **CLAIM**

The ornamental design for a folding knife, as shown and described.

DESCRIPTION

FIG. 1 is a top right perspective of a knife in an open position, according to a first embodiment of the present invention;

FIG. 2 is a first side elevation view of the knife of FIG. 1 in an open position;

FIG. 3 is a second side elevation view of the knife of FIG. 1 in an open position;

FIG. 4 is a back elevation view of the knife of FIG. 1 in an open position;

FIG. 5 is a front elevation view of the knife of FIG. 1 in an open position;

FIG. 6 is a bottom plan view of the knife of FIG. 1 in an open position;

FIG. 7 is a top plan view of the knife of FIG. 1 in an open position;

FIG. 8 is a top right perspective of the knife of FIG. 1 in a closed position;

FIG. 9 is a first side elevation view of the folding knife of FIG. 1, in a closed position;

FIG. 10 is a top right perspective of a knife in an open position, according to a second embodiment the present invention;

FIG. 11 is a first side elevation view of the knife of FIG. 10 in an open position;

FIG. 12 is a second side elevation view of the knife of FIG. 10 in an open position;

FIG. 13 is a back elevation view of the knife of FIG. 10 in an open position;

FIG. 14 is a front elevation view of the knife of FIG. 10 in an open position;

FIG. 15 is a bottom plan view of the knife of FIG. 10 in an open position;

FIG. 16 is a top plan view of the knife of FIG. 10 in an open position;

FIG. 17 is a top right perspective of the knife of FIG. 10 in a closed position; and,

FIG. 18 is a first side elevation view of the folding knife of FIG. 10, in a closed position.

The broken lines in FIGS. 10 through 18 depict portions of the pocket folding knife in which the design is embodied that are not considered part of the claimed design.
